[57] CLAIM

The ornamental design for a photography support bracket, as shown and described.

DESCRIPTION

FIG. 1 is a perspective view of a photography support bracket showing my new design;

FIG. 2 is a left side elevational view thereof;

FIG. 3 is a right side elevational view thereof;

FIG. 4 is a bottom plan view thereof;

FIG. 5 is a right end elevational view thereof, the left end view being a mirror image thereof.
